Specification for Design.

Patented July 23, 1912.

Application filed December 2, 1911. Serial No. 663,617. Term of patent 14 years.

To all whom it may concern:

Be it known that I, HENRY ACKERMAN, a citizen of the United States, and a resident of Clifton Park, Weehawken, in the county of Hudson and State of New Jersey, have invented a new, original, and ornamental Design for a Setting for Gems, of which the following is a specification, reference being had to the accompanying drawing, forming part thereof.

Figure 1 is a top plan of the setting, showing mainly the shape of the base; and

Fig. 2 is a side elevation of the setting, showing the manner in which the base is turned up along the rim, to form flaring sides.

I claim:

The ornamental design for a setting for gems, as shown.

HENRY ACKERMAN.
